Joseph Loecy, Jr., Euclid, Ohio

Application December 24, 1949, Serial No. 6,838

Term of patent 14 years

(Cl. D54—13)

To all whom it may concern:

Be it known that I, Joseph Loecy, Jr., a citizen of the United States, residing at Euclid, county of Cuyahoga and State of Ohio, have invented a new, original, and ornamental Design for Diamond Tool for Dressing Grinding Wheels, of which the following is a specification, reference being had to the accompanying drawing, forming part thereof.

Fig. 1 is a side elevation of a diamond tool for dressing grinding wheels, showing my new design;

Fig. 2 is a front end elevation thereof; and
Fig. 3 is a rear end elevation thereof.

I claim:

The ornamental design for a diamond tool for dressing grinding wheels, as shown.

JOSEPH LOECY, JR.
